STRINGED MUSICAL INSTRUMENT

John J. Moore, Winsted, Conn., assignor to Gibson, Inc., Kalamazoo, Mich., a corporation of Michigan

Application August 23, 1940, Serial No. 353,950

18 Claims. (Cl. 84—312)

This invention relates to musical instruments, and has special reference to a guitar of the type commonly called a steel guitar.

One important object of the invention is to provide a guitar of this character wherein the strings pertaining to a definite chord may be simultaneously changed in pitch by the depression of a pedal.

A second important object of the invention is to provide a device of this character wherein with six pedals no less than fifteen chords may be obtained.

A third important object of the invention is to provide an arrangement in such a guitar whereby all of the chords are produced on open strings, the key of said chords being varied in the conventional manner with the steel or bar.

A fourth important object of the invention is to provide a device of this character tuned to what is known as a seventh tuning, by means of the conventional tuning keys, it being preferable to use a D seventh tuning instead of the ordinary E seventh tuning, although this may be used if preferred.

With the above and other objects in view, as will be hereinafter apparent, the invention consists in certain novel features of construction and combinations of parts hereinafter fully described, illustrated in the accompanying drawings, and specifically pointed out in the appended claims.

In the accompanying drawings, like characters of reference indicate like parts in the several views, and—

35 Figure 1 illustrates a plan view of the instrument;

Figure 2 illustrates an enlarged plan view of the pedal group used therein;

40 Figure 3 illustrates a side elevation of such pedal group with the pedals raised;

Figure 4 illustrates a side elevation of the complete instrument;

45 Figure 5 illustrates a detailed section on the line 5—5 of Fig. 2 with one of the pedals shown in raised position in dotted lines and in depressed position in full lines;

Figure 6 illustrates an enlarged plan view of what may be termed the tuning box;

50 Figure 7 illustrates a section on the line 7—7 of Fig. 6;

Figure 8 illustrates a section on the line 8—8 of Fig. 6;

55 Figure 9 illustrates a section on the line 9—9 of Fig. 6 showing the parts illustrated as in the position when a pedal has been depressed;

Figure 10 illustrates a perspective view of one of the yokes used herein;

Figure 11 illustrates a perspective view of one of the levers used herein;

Figure 12 illustrates a perspective view of another of said levers; and

Figure 13 illustrates a perspective view of a guide post for supporting the spring to return the levers.

In carrying out the objects of this invention, there is provided a body 10, preferably in the form of a hard wood plank or board table, approximately two inches thick and 40 inches long, and about 8 inches wide. This board table is supported at what may be termed the key end 15 by a leg 11 and at the tuning end by a pair of diverging legs 12 so that the structure is supported as on a tripod. Between the legs 12 there is located a pedal frame comprising a platform 13 supported at its rear portion by a member 14 so that the platform is inclined from the rear to the front downwardly. Adjacent the rear of the platform is a pair of bearing members 15 which support a shaft 16 whereon is mounted a series of six pedals numbered respectively 17, 18, 19, 20, 21, and 22. An inverted U-shaped yoke 23 has its ends attached to the board 13 and its central portion extends across the board in spaced relation to the shaft 16 and over the pedals to form a stop, limiting their upward movement. The ends of Bowden wire cables 24 are secured to the pedals and pass through guides 25 on the stop.

Each end of the board 10 is beveled and at the end adjacent the pedal frame there is mounted a lever box which consists of a base member 26, from the front edge of which rises a series of uprights 27, and through the top of these uprights extends a shaft 28. On this shaft 28 are pivoted the yokes 29, 30, 31, 32, 33 and 34, these yokes being of gradually decreasing width so that they nest, one within the other. Each of these yokes is connected by a Bowden wire cable to a respective pedal 17 so that when the pedal is depressed the yokes are correspondingly depressed, that is to say, when pedal 17 is depressed, yoke 29 is depressed and so forth. Mounted on the shaft 28 are five bell crank levers 35, the shaft passing through an opening 36 at the angle of each of these levers. One arm of each lever 35 extends rearwardly from the shaft 28 to pass beneath the cross bars of the yokes and is urged upwardly by a spring 37 to engage against a stop bar 38 supported from the plate 26. The other arm of each lever 35 depends at 55

its forward end from the shaft 23 and has at its lower end an opening 39 for the reception of one of the wires or strings S of the instrument. A second shaft or bar 40 extends through the members 27 rearwardly and below the shaft 23. Other bell crank levers 41 likewise have substantially horizontal arms extending beneath the cross bars of the yokes and have their forward arm extending downwardly and provided at its lower end with an opening 42 pivoting on the shaft or bar 40. Above the opening 42 one or more openings 43 is provided for securing one of the wires or strings S. The cross bars of the yokes are provided with a series of tuning screws 44 which are adapted to engage the longer arms of the levers 35 and 41 to depress the same and these are positioned and are in number different for the different yokes, for purposes which will hereinafter be understood.

20 A bridge 45 is provided just forwardly of the plate 26, and adjacent the other end of the base or board 10 is a bridge 46 over which the strings S pass to the usual tuning screws 47.

For the purposes of explaining the operation of the device, let it be supposed that the eight strings common to guitars of this type have been tuned to a D seventh tuning. If the pedal 22 be depressed, then the yoke 34 will likewise be depressed. There are four screws 44 on that yoke and these screws are positioned over the three D string levers and the C string lever, as shown in Fig. 6. The depression of the first D string lever will cause tightening of that string while the depression of the other two will cause slackening or increased tension of that string. Likewise, the C string lever will move to reduce the tension on the C string. By adjustment of the screws 44, these increases and reductions of tension are so regulated as to change the strings so that in open use they will read D#, A, F#, D, B, A, F#, D. With this as an example, attention is invited to the following table showing the effect of the depression of the several pedals:

45.		Strings								45
		1st	2nd	3rd	4th	5th	6th	7th	8th	
	Open	D	A	F#	D	C	A	F#	D	
50:	#17 pedal	D	A	F#	D	B	G	F	D	
	#18 pedal	D _b	A	F#	D	B	A _b	E _b	D	
	#19 pedal	D	A _#	F#	D	A _#	Not used	F#	D	
	#20 pedal	D	A	F	D	C	A	F	D	
	#21 pedal	B	A	F#	D	B	A	F#	D	
	#21 _{1/2} down	C	A	F#	D	C	A	F#	D	
	#21 _{1/2} down	D _b	A	F#	D	B	A	F#	D	
	#22 pedal	D _#	A	F#	D _b	Not used	A	F#	D _b	
55:	#17 and #18 pedals	D _b	A	F#	D	Not used	Not used	Not used	Not used	55
	#19 and #20 pedals	D	A _#	F#	D	A _#	A _b	F#	D	
	#20 and #21 _{1/2} down	C	A	F	D	C	A	F	D	
	#20 and #21 pedals	B	A	F	D	B	A	F	D	
	#21 _{1/2} down and #22	C	A	F#	D _#	Not used	A	F#	D _#	
	#21 and #22 pedals	B	A	F#	D _#	B	A	F#	D _#	

60 It will be noted from the above that with the six pedals, fifteen chords can be formed on open strings. It is obvious that by varying the tuning of the strings of the screws 47 and varying the positions of the screws 44 the same device may be used in a wide variety of instruments such as guitars, banjos, mandolins and the like, and while a guitar has been here described specifically, it is to be understood that the invention is not limited to the use of the device in a guitar but 70 the same may be applied to any suitable musical instrument.

I claim:

1. In a stringed musical instrument, a pedal bank, a series of tiltable yokes each operatively connected to a pedal of said bank, a series of

string tensioning levers extending beneath and operated by said yokes and engaging said yokes upon depression of the pedals and supported to effect increase of tension in the strings to which they are attached, and a second series of string tensioning levers extending beneath and operated by and engaging said yokes and supported to relax tension of the strings to which they are attached. 5

2. In a stringed musical instrument, a pedal bank, a series of tiltable yokes each operatively connected to a pedal of said bank, a series of string tensioning levers extending beneath and operated by said yokes and engaging said yokes upon depression of the pedals and supported to 10 effect increase of tension in the strings to which they are attached, a second series of string tensioning levers extending beneath and operated by and engaging said yokes and supported to 15 relax tension of the strings to which they are attached, and means carried by the yokes and engaging said levers to regulate the extent of movements of said levers. 20

3. In a stringed musical instrument, a pedal bank, a series of tiltable yokes each operatively connected to a pedal of said bank, a series of string tensioning levers extending beneath and operated by said yokes and engaging said yokes upon depression of the pedals and supported to 25 effect increase of tension in the strings to which they are attached, a second series of string tensioning levers extending beneath and operated by and engaging said yokes and supported to 30 relax tension of the strings to which they are attached, and screws projecting through said 35 yokes and engaging said levers to regulate the extent of movement of the latter.

4. In a stringed musical instrument, a pedal bank, a series of tiltable yokes each operatively connected to a pedal of said bank, a series of string tensioning levers extending beneath and operated by said yokes and engaging said yokes upon depression of the pedals and supported to 40

effect increase of tension in the strings to which they are attached, and a second series of string tensioning levers extending beneath and operated by and engaging said yokes and supported to relax tension of the strings to which they are attached, said yokes being mounted on a common pivotal axis and in nested relation. 60

5. In a stringed musical instrument, a pedal bank, a series of tiltable yokes each operatively connected to a pedal of said bank, a series of string tensioning levers extending beneath and operated by said yokes and engaging said yokes upon depression of the pedals and supported to 70 effect increase of tension in the strings to which they are attached, a second series of string tensioning levers extending beneath and operated 75

5 by and engaging said yokes and supported to relax tension of the strings to which they are attached, and means carried by the yokes and engaging said levers to regulate the extent of movements of said levers, said yokes being mounted on a common pivotal axis and in nested relation.

6. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, and screws projecting through said yokes 10 and engaging said levers to regulate the extent of movement of the latter, said yokes being mounted on a common pivotal axis and in nested relation.

7. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, 25 an elongated base member, means supporting said yokes and levers at one end of said base member, and string tuning screws at the other end of said base member.

8. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, 40 means carried by the yokes and engaging said levers to regulate the extent of movements of said levers, an elongated base member, means supporting said yokes and levers at one end of said base member, and string tuning screws at the other end of said base member.

9. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, screws projecting through said yokes and engaging said levers to regulate the extent of movement of the latter, an elongated base 65 member, means supporting said yokes and levers at one end of said base member, and string tuning screws at the other end of said base member.

10. In a stringed musical instrument, a pedal bank, a series of tilttable yokes each operatively connected to a pedal of said bank, a series of

5 string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, said yokes being mounted on a common pivotal axis and in nested relation, an elongated 10 base member, means supporting said yokes and levers at one end of said base member, and string tuning screws at the other end of said base member.

11. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, 25 means carried by the yokes and engaging said levers to regulate the extent of movements of said levers, said yokes being mounted on a common pivotal axis and in nested relation, an elongated base member, means supporting said yokes and 30 levers at one end of said base member, and string tuning screws at the other end of said base member.

12. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which 40 they are attached, a second series of string tensioning levers extending beneath and operated by and engaging said yokes and supported to relax tension of the strings to which they are attached, screws projecting through said yokes and 45 engaging said levers to regulate the extent of movement of the latter, said yokes being mounted on a common pivotal axis and in nested relation, an elongated base member, means supporting said yokes and levers at one end of said base member, and string tuning screws at the other end of said base member.

13. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, and a second series of string 55 tensioning levers extending beneath and operated by and engaging said yokes and supported to relax tension of the strings to which they are attached, said series of levers being bell crank levers each having one arm in engagement with 60 the yokes, the first series being pivoted at their angles and having string connections at the ends of their other arms and the second series being pivoted at the ends of their remaining arms and having string connections between their angles 65 and pivots.

14. In a stringed musical instrument, a pedal bank, a series of tilttable yokes each operatively connected to a pedal of said bank, a series of string tensioning levers extending beneath and 75

operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, and means carried by the yokes and engaging said levers to regulate the extent of movements of said levers, said series of levers being bell crank levers each having one arm in engagement with the yokes, the first series being pivoted at their angles and having string connections at the ends of their other arms and the second series being pivoted at the ends of their remaining arms and having string connections between their angles and pivots.

15. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, and screws projecting through said yokes and engaging said levers to regulate the extent of movement of the latter, said series of levers being bell crank levers each having one arm in engagement with the yokes, the first series being pivoted at their angles and having string connections at the ends of their other arms and the second series being pivoted at the ends of their remaining arms and having string connections between their angles and pivots.

16. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, an elongated base member, means supporting said yokes and levers at one end of said base member, and string tuning screws at the other end of said base member, said series of levers being bell crank levers each having one arm in engagement with the yokes, the first series being pivoted at their angles and having string connections at the ends of their other arms and the second series being pivoted at the ends of their remaining arms and having string connections between their angles and pivots.

pivoted at their angles and having string connections at the ends of their other arms and the second series being pivoted at the ends of their remaining arms and having string connections between their angles and pivots.

17. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, means carried by the yokes and engaging said levers to regulate the extent of movements of said levers, an elongated base member, means supporting said yokes and levers at one end of said base member, and string tuning screws at the other end of said base member, said series of levers being bell crank levers each having one arm in engagement with the yokes, the first series being pivoted at their angles and having string connections at the ends of their other arms and the second series being pivoted at the ends of their remaining arms and having string connections between their angles and pivots.

18. In a stringed musical instrument, a pedal bank, a series of tilttable yokes each operatively connected to a pedal of said bank, a series of string tensioning levers extending beneath and operated by said yokes and engaging said yokes upon depression of the pedals and supported to effect increase of tension in the strings to which they are attached, a second series of string tensioning levers extending beneath and operated by and engaging said yokes and supported to relax tension of the strings to which they are attached, screws projecting through said yokes and engaging said levers to regulate the extent of movement of the latter, an elongated base member, means supporting said yokes and levers at one end of said base member, and string tuning screws at the other end of said base member, said series of levers being bell crank levers each having one arm in engagement with the yokes, the first series being pivoted at their angles and having string connections at the ends of their other arms and the second series being pivoted at the ends of their remaining arms and having string connections between their angles and pivots.

JOHN J. MOORE. 55
